UNITED STATES PATENT OFFICE

130,112

DESIGN FOR A WATCH BRACELET STRAP

John P. Schultheiss, Attleboro, Mass., assignor to R. F. Simmons Company, Attleboro, Mass., a partnership consisting of Harold E. Sweet and Hayward H. Sweet

Application February 4, 1941, Serial No. 98,740

Term of patent 7 years

To all whom it may concern:

Be it known that I, John P. Schultheiss, a citizen of the United States, residing in the city of Attleboro, county of Bristol, and Commonwealth of Massachusetts, have invented a new, original, and ornamental Design for a Watch Bracelet Strap, of which the following is a specification, reference being had to the accompanying drawing, forming a part thereof, in which:

Fig. 1 is a plan view of the watch bracelet strap showing my new design; and
Fig. 2 is an edge view of the same.

I claim:

The ornamental design for a watch bracelet strap, substantially as shown.

JOHN P. SCHULTHEISS.
